CLAIM

The ornamental design for a compression molding press for mounting metallurgical specimens, as shown.

DESCRIPTION

FIG. 1 is a perspective view of a compression molding press for mounting metallurgical specimens embodying my new design.

FIG. 2 is a front elevational view thereof.

FIG. 3 is a bottom plan view thereof.

FIG. 4 is a top plan view thereof.

FIG. 5 is a right side elevational view thereof.

FIG. 6 is a rear elevational view thereof.

FIG. 7 is a left side elevational view thereof.
